UNITED STATES PATENT OFFICE.

WILLIAM M. SCOTT, OF PHILADELPHIA, PENNSYLVANIA, ASSIGNOR TO THE CUTTER ELECTRICAL AND MANUFACTURING COMPANY, A CORPORATION OF NEW JERSEY.

CIRCUIT-BREAKER.

1,125,745.

Specification of Letters Patent.

Patented Jan. 19, 1915.

Application filed March 27, 1908. Serial No. 423,751.

To all whom it may concern:

Be it known that I, WILLIAM M. SCOTT, a citizen of the United States, residing at Philadelphia, in the county of Philadelphia, 5 State of Pennsylvania, have invented a new and useful Circuit-Breaker, of which the following is a specification.

My invention relates to electrical switches suitable for making or breaking or controlling an electric circuit carrying currents of great volume and of considerable potential, and more particularly relates to an automatic circuit breaker.

My invention resides in an electrical switch comprising main and shunt members, the main and shunt members being pivotally mounted independently of each other, though they may be concentrically pivoted.

It is the object of my invention to provide a pivoted main contact member and an independently pivoted shunt or secondary contact member so that the secondary or shunt contact operates independently of the main switch member to break the circuit 25 after and to close the circuit before the main switch member. The independence of the secondary or shunt contact from the main contact member, secured by this independent pivoting, results in a mode of operation 30 different from prior structures in which the secondary or shunt contact has been pivoted upon or to the main contact, and carried through space by the main contact, to secure independent movement of the shunt or 35 secondary contact with respect to the main contact. In my apparatus the shunt contact is not supported on and carried through space by the main contact, but is independently mounted.

My invention resides also in other features hereinafter described and claimed.

For an illustration of some of the forms my invention may take, reference is to be had to the accompanying drawings, in 45 which:

Figure 1 is a side elevation of a circuit breaker embodying my invention. Fig. 2 is a side elevation of the pivoted arm adapted to carry the main contact. Fig. 3 is a side 50 elevation and Fig. 4 is a front elevation of the independently pivoted arm adapted to carry a secondary or shunt contact. Fig. 5 is a front elevation of the circuit breaker shown in Fig. 1. Fig. 6 is an edge view of

the intermediate stationary metallic shunt contact. Fig. 7 is a side elevation of a modified construction in which the shunt contact is pivoted independently of the main contact. Fig. 8 is a front elevation of the parts shown in Fig. 7. Fig. 9 is an enlarged view of the spring member shown in Fig. 7. Fig. 10 is a fragmentary side elevation showing the main and shunt arms pivoted eccentrically with respect to each other.

Referring to the drawings, 1 represents a suitable base of any suitable insulating material, such, for example, as marble or slate, upon which are mounted, one vertically above the other, the main contact terminals 2 and 3 adapted to be engaged and bridged by the laminated bridging contact 4 secured to and carried by the arm 5, pivoted at 6, to the housing or bracket 7, which is, in turn, secured upon the base 1.

The operating lever 8, having the operator's handle 9, is pivoted to the housing 7 at 10 and extends inwardly beyond the pivot 10 to form a toggle link 11, of a pair of toggle links, the other toggle link 12 being pivoted at 13 to the link 11 and at 14 to the arm 5.

A spring 15, under tension with the parts in circuit closing position, is connected at one end to the toggle link 11 and at its inner end to the arm 5.

The latch 16 is pivoted at 17 to the lug 18, upon the bracket 7, and is adapted to engage the roller 19 pivoted on the operating lever 8. The latch actuating member 20 is also pivoted at 17 and engages with the adjustable screw 21, carried by it, upon the top of the latch 16. The tail 22 of the latch actuator 20 extends into the path of travel of the armature 23 of the electro-magnetic tripping device, such armature coöperating with the pole piece 24 upon the core 25, both of iron, the core 25 being partially surrounded by the plate conductor 26, which connects at one end with the block 27, forming one terminal of the circuit breaker, and its other end is disposed vertically and forms the lower main contact 3 engaged by the laminated contact 4. The thumb nut 28 serves to adjust the armature 23 to different heights, and the handle 29 serves for manually tripping the breaker.

Disposed across the top horizontal face of the main terminal block 2, and extending

downwardly on each side of the terminal block 2, is the intermediate stationary metallic shunt contact 30, of channel shape, which is shown isolated and in front edge view in Fig. 6. With the downward extensions or ears 31, 31 engage the movable metallic shunt contacts 32, 32 formed on the ends of the laterally yielding plates 33, 33 secured to and in electrical communication 10 with the main laminated contact 4.

In closing the switch, the movable metallic contacts 32, 32 engage by overlapping and side rubbing action upon the stationary metallic contacts 31, 31, before laminated 15 contact 4 engages the main contacts 2 and 3; and in opening circuit these metallic shunt contacts separate after main bridge 4 has separated from the main terminals 2 and 3, but before the shunt carbons separate.

Disposed upon the top of the stationary metallic shunt contact 30 and secured by screws 34, passing through it, the shunt contact 30, and into the main terminal block 2, is the spring metal plate 35 supporting the stationary shunt carbon 36. With the carbon 36 cooperates the movable shunt carbon 37 supported upon the rigid plate 38 which is, in turn, secured to a web or plate 39 joining the upper ends of the rigid arms 40, pivoted to the bracket or housing 7 at 6, concentrically with the arm 5. A spring 41 joins each of the similar arms 40 with the laminated contact 4, such spring being under tension when the parts are in circuit closing position. In electrical communication with the carbon 37 is a conductor 42 which extends downwardly and remains in electrical communication with the lower main terminal 3.

The operation is as follows: Assuming the parts in circuit closing position, as shown in Fig. 1, upon an excessive or pre-determined current flow in the circuit (in which the breaker is connected through the studs 43 and 44, communicating respectively with the upper main terminal 2 and the piece 27,) the core 25 and its pole pieces 24 will be sufficiently magnetized to attract upwardly the armature 23 pivoted at 23', delivering a blow 50 to the under side of the tail 22 of the latch actuator 20, rotating the actuator 20 upon the pivot 17 and striking upon the top of latch 16, withdrawing the same from the roller 19 and so releasing the operating lever 55 8. The toggle 11, 12 being slightly undertraveled, will collapse or knee, under the influence of the spring 15 and the resilience of the main contact 4 thus causing the arm 5 to rotate away from the base and separate 60 the main contact 4 from the main contacts 2 and 3 to break circuit. During this time the carbon 37 remains in engagement with carbon 36, the main contact 4 moving about its pivot 6 independently of the carbon 37 65 and of its supporting arm 40. Soon after

the main laminated contact 4 has separated from the main terminals 2 and 3, the metallic shunt contacts 32 separate from the companion contacts 31. At a slightly later stage, the main contact 4 has moved outwardly from the terminals 2 and 3 to a position where it engages the arms 40 and from this point on the carbon 37 is moved away from carbon 36, the arm 40 moving independently upon its pivot 6. The carbon 36, 70 75 due to the resilience of its support 35, may follow the carbon 37, such resilience being provided to insure a satisfactory adjustment of one carbon upon the other, and early circuit closure at the carbons. The 80 final break of the circuit takes place at the carbons and the arcing is confined to them, as well understood in the art.

From this construction it follows that the movable shunt carbon, rigidly supported 85 upon a rigid pivoted arm, is not supported either pivotally, or otherwise, upon the main movable contact, and is, therefore, not carried by the main movable contact through space. The shunt carbon 37 moves through 90 space independently due to the independent pivoting of the rigid supporting arm 40.

While the spring 41 is shown connected between the arm 40 and the main contact 4, it is to be understood that it may be connected between the arm 40 and some fixed member or portion of the instrument, as for example, to the bracket 7.

In Figs. 7 and 8 are shown the movable parts of a switch or breaker which are the same as those shown in Fig. 1, except that the spring 41 is not present. The tubular member 45 is pivoted at 46 to the arm 40. Engaging within the member 45 is a member 47 pivoted at 48 to the toggle link 11. 105 A spiral spring 49 surrounds the members 45 and 47 and is confined between their heads, and is normally under compression thus tending to force the members 45 and 47 apart. From this, it follows that when the toggle 11, 12 is collapsed, the spring 49 holds the arm 40 stationary and, therefore, the carbon 37 against carbon 36 until the main laminated member 4 engages the arm 40 to carry it away from the base. 110 115

In the arrangements of both Fig. 1 and Fig. 7 the arms 40 are pivoted independently of though concentrically with arm 5. It is to be understood, however, that arm 40 may be pivoted independently of arm 5 120 at other points, *i. e.*, not concentrically, as shown in Fig. 10 where arm 40 is pivoted at 6' at a distance from pivot 6 of arm 5.

What I claim is:

1. In an electric switch, a stationary main contact block, a pivoted laminated contact co-operating therewith, a shunt contact carried by said laminated contact and rigid therewith in the direction of movement thereof and adapted to make contact at a 125 130

side of said main contact block, a rigid arm pivoted independently of said laminated contact, a second shunt contact carried by said arm, and switch operating means positively connected only with said laminated contact.

2. In an electric switch, a pivoted main movable contact member, a rigid arm pivoted independently of said main contact, switch operating means positively connected only to said main contact, and a telescopic connection interposed directly between said operating means and said arm.

3. In an electric switch, a pivoted main movable contact, an arm pivoted independently of said contact, a shunt contact carried by said arm, a toggle connected to said main contact, and a yielding connection in-

terposed directly between said arm and a link of said toggle.

4. In an electric switch, a pivoted main movable contact, an arm pivoted independently of said contact, a shunt contact carried by said arm, a toggle connected to said main contact, and a yielding telescopic connection interposed directly between said arm and a link of said toggle remote from said main contact.

In testimony whereof I have hereunto affixed my signature in the presence of the two subscribing witnesses.

WILLIAM M. SCOTT.
